UNITED STATES PATENT OFFICE.

M. A. FURBUSH, OF PHILADELPHIA, PENNSYLVANIA.

IMPROVEMENT IN DRYING-CYLINDERS FOR DRYING PAPER, WARP-THREADS, &c.

Specification forming part of Letters Patent No. 44,524, dated October 4, 1864

To all whom it may concern:

Be it known that I, M. A. FURBUSH, of Philadelphia, Pennsylvania, have invented an Improved Drying-Cylinder; and I do hereby declare the following to be a full, clear, and exact description of the same, reference being had to the accompanying drawings, and to the letters of reference marked thereon.

My improved drying-cylinder consists of an exterior cylindrical casing caused to revolve round (but not in contact with) and to derive its heat from an inner cylindrical casing to which steam is admitted.

The object of my invention is to avoid the use of the stuffing-boxes which are necessarily employed in connection with ordinary drying-cylinders, and which are apt to leak and permit the escape of steam, to the detriment of the warp-threads, paper, or other material to be dried.

In order to enable others skilled in the art to make and use my invention, I will now proceed to describe its construction and operation.

On reference to the accompanying drawings, which forms a part of this specification, Figure 1 is a side view of sufficient of a machine for drying warp-threads to illustrate my invention; Fig. 2, a transverse vertical section on line 1 2, Fig. 1; Fig. 3, a transverse section of the drying-cylinder, and Fig. 4 an end view of the same.

Similar letters refer to similar parts throughout the several views.

A represent the side frames of a machine for drying warp-threads which may be similar to other machines of this class in every particular, except the drying-cylinders and their bearings, to the construction of which my invention especially appertains. Each drying-cylinder is composed of a cylindrical casing B, contained within an outer casing, C, the latter being as close as possible to the former without being in actual contact with it. The outer casing, C, has at each end a tubular

journal arranged to revolve on and with rollers b b, which are hung loosely to pins on a bracket, D, one bracket being secured to each frame. Through one of the journals a passes a tube, F, communicating with a pipe, G, through which steam is introduced into the interior of the cylinder, and through the opposite journal passes a tube, F', projecting into the inner casing, B, within which it is bent at right angles, this tube serving as a passage for the steam from the casing B to the waste-pipe H. Both of the tubes F and F' are permanently secured to or form a part of the inner or cylindrical casing, which, with the pipes G a H, remains stationary, while the outer casing is caused to revolve by the warp-thread or paper which traverses in contact with it. By this arrangement I avoid the use of the stuffing-boxes which are employed in connection with ordinary drying-cylinders, and which are a source of much annoyance on account of their liability to leak and permit the escape of steam, to the injury of the warp-thread, paper, or other material to be dried. By causing the outer casing to revolve in close contiguity, but not in absolute contact with the inner casing, sufficient heat is transmitted from the latter to the former to give the desired drying effect.

I claim as my invention and desire to secure by Letters Patent—

A drying-cylinder consisting of an exterior cylindrical casing caused to revolve around (but not in contact with) and to derive its heat from an inner cylindrical casing to which steam is admitted, all substantially as and for the purpose herein set forth.

In testimony whereof I have signed my name to this specification in the presence of two subscribing witnesses.

M. A. FURBUSH.
